UNITED STATES PATENT OFFICE.

CYRIL N. OUTERBRIDGE, OF CHARLOTTESVILLE, VIRGINIA.

INTERNAL-COMBUSTION ENGINE.

1,211,339.

Specification of Letters Patent.

Patented Jan. 2, 1917.

Application filed November 29, 1915. Serial No. 64,056.

To all whom it may concern:

Be it known that I, CYRIL N. OUTERBRIDGE, a citizen of the United States, residing at Charlottesville, in the county of Albemarle and State of Virginia, have invented new and useful Improvements in Internal-Combustion Engines, of which the following is a specification.

This invention relates to internal combustion engines, the broad object in view being to produce an engine of the class referred to which will run with greater smoothness and therefore with better efficiency in the matter of power than the present day type of internal combustion engine.

The particular object of the present invention is to provide an engine embodying what may be termed a headless cylinder or, in other words, a cylinder the outer end of which is entirely open, in conjunction with a reciprocating piston working in said cylinder and connected to the crank shaft by the usual connecting rod, the engine further embodying an internal stationary cylindrical abutment around which the piston works, the explosive mixture being admitted to the interior of the piston and being exploded between the stationary abutment and the inner wall of the piston head so as to drive the piston upwardly instead of downwardly as in the present day internal combustion engine, thereby exerting an upward pull on the crank shaft in place of the present downward thrust on said crank shaft. In view of such arrangement, the piston head is kept cool and also the head of the abutment, the piston head being always in contact with the atmospheric temperature and the head of the abutment being cooled by the air contained in the crank case. Thus the engine is maintained at a uniform temperature and therefore delivers uniform power, the final result being an engine of smoother running qualities produced by the inability of the parts to become overheated.

With the above and other objects in view, the invention consists in the novel construction, combination and arrangement of parts, as herein described, illustrated and claimed.

In the accompanying drawings:—Figure 1 is a sectional view of an internal combustion engine taken diametrically of the cylinder. Fig. 2 is a view taken diametrically of the cylinder at right angles to Fig. 1. Fig. 3 is a cross section on the line 3—3 of Fig. 2.

Referring to the drawings A designates the crank case which is shown as comprising a removable bottom section *a* by detaching which the bearing caps *a'* for the crank shaft bearings may be removed to allow the crank shaft to be removed through the bottom of the crank case and also to enable access to be had to the crank shaft bearings and also the connecting rod bearings without dismounting the cylinders, pistons, valves, manifolds and other parts, as now required.

Mounted in fixed relation to the crank case A is the cylinder B shown as formed with a water jacket *b* and intake and exhaust ports *b'* and *b''* with which communicate intake and exhaust pipes or manifolds C and D, respectively. A reciprocating piston E works back and forth within the cylinder B but is of less external diameter than the internal diameter of the cylinder B in order to provide for a sleeve valve which is shown as comprising an inner tubular section *c* and an outer tubular section *c'*, said sections being provided with inlet and outlet ports properly located with respect to the intake and exhaust ports of the cylinder and piston, said sleeve valves *c* and *c'* being operated by connecting rods *d* and *e* from a valve-actuating shaft designated generally at F.

The piston E is of tubular formation, is open at its inner end and closed at its outer end by a head G which is shown as carrying a spark plug *g*. Within the cylinder and piston there is arranged a stationary hollow cylindrical abutment H provided with a closed head *h* at the outer end thereof, the space between the heads G and *h* forming a combustion chamber I. The abutment H bears a fixed relation to the crank case A and cylinder B and is provided in the outer face thereof with packing rings *h'* which work in contact with the inner wall of the piston E. The abutment H is formed at diametrically opposite sides with longitudinally slots *k* in which works the wrist pin K of the connecting rod L attached to the crank shaft M. The piston E is provided at diametrically opposite places with longitudinally extending slots *e'* to allow for the admission of charges to the combustion chamber I and the escape of the burned gases through the exhaust ports of the valves and cylinder.

It will, of course, be understood that any

number of cylinders may be employed as found desirable and as indicated in Fig. 3, and used in connection with a common crank case in accordance with the present well known practice. In view of the fact that the outer end of the cylinder is open at all times, the piston head G is kept in a cool condition and prevented from overheating and the same is true of the head h of the stationary abutment II as the latter is always under the influence of the comparatively cool air in the crank case A. This not only prevents the engine from overheating but it tends to prevent the rapid accumulation of carbon. Furthermore, the sleeve valves radiate the heat therefrom both at their outer and inner ends thus preventing them from becoming overheated and binding. The valves may also be given additional lubrication whenever desired through the open end of the cylinder. By preventing the working parts of the engine from becoming overheated and maintaining said parts at a

practically uniform temperature, an engine of greater efficiency, more uniform power, and smoother running qualities is obtained.

Having thus described my invention, I claim:

In an internal combustion engine, the combination of a crank case, a crank shaft journaled therein, a cylinder having a fixed relation to the crank case and open at both ends, a stationary cylindrical abutment having a fixed relation to the crank case closed at its outer end and open at its inner end, a tubular piston working in said cylinder and around said cylindrical abutment and having its head exposed to the atmosphere, and a connecting rod between said piston and crank shaft.

In testimony whereof I affix my signature in presence of two witnesses.

CYRIL N. OUTERBRIDGE.
